United States Patent

Des. 236,961
Patented Sept. 30, 1975

236,961

BALANCE SCALE

Deborah J. Gleason, Norfolk, Mass., assignor to
Xerox Corporation, Stamford, Conn.

Filed Mar. 25, 1974, Ser. No. 454,341

Term of patent 14 years

Int. Cl. D10—04

U.S. Cl. D10—90

FIG. 1

FIG. 2

FIG. 3

FIG. 1 is a right front perspective view of a balance scale showing my new design;

FIG. 2 is a left front perspective view thereof; and
FIG. 3 is a rear perspective view thereof.

I claim:

The ornamental design for a balance scale, substantially as shown.
